Truss Bridge.

No 11,322.

Patented July 18, 1854.

UNITED STATES PATENT OFFICE.

SAM'L CHAMPION AND THOMAS CHAMPION, OF WASHINGTON, DISTRICT OF COLUMBIA.

BRIDGE.

Specification of Letters Patent No. 11,322, dated July 18, 1854.

To all whom it may concern:

Be it known that we, SAMUEL CHAMPION and THOMAS CHAMPION, of the city of Washington, District of Columbia, have invented a new Mode of Constructing Bridges; and we do hereby declare that the following is a full and exact description thereof, reference being had to the accompanying drawings, and to the letters of reference marked thereon, in which—

Figure 1 is an elevation of a bridge constructed after our improved plan. In this view two sections are shown as component parts of the bridge, each section being mounted upon its own pier. Figs. 3, 4, 5, 6, 7, 8, 9 and 10, represent respectively views of the details of construction, which will presently be more particularly described.

The bridge as represented in the drawings consists of two rigid sections, each of which is supported on a pier beneath its center. Each section consists of two parallel frames (A) united by the floor timbers and diagonal braces. These frames form the sides of the bridge, and each consists of a central foot or hub (B) and a vertical main post (C) resting upon this hub. The top of this post forms the center, whence a series of suspension rods (D) radiate, while the hub or foot upon which the post stands, is the center whence a series of struts or braces (E) radiate. This foot has a concave bottom to fit like a saddle upon the lower strut, which lies horizontally, or extends the entire length of the section of the bridge, is on a level with the roadway and carries the floor timbers. A suitable number of oblique struts, radiate between the center or vertical post and the horizontal strut. A vertical clamp post (F) connects the outer extremities of each of the oblique struts (E) with the horizontal strut (G). Suspension rods (D) extending from the head of the center post, are connected to the top, foot, and intermediate points of each clamp post. Each clamp post (F) has a socket at its upper extremity that fits over the outer extremity of a strut. Each suspension rod whether it terminates at, or passes beyond a clamp post, is firmly connected thereto, so that the whole frame may be united into one rigid system. As the struts and suspension rods have less weight to sustain, as they recede from the centers of tension and compression, they may therefore be proportionately di-

minished in size and weight with advantage to the strength and durability of the bridge, the parts of which distant from the center, might be made so heavy that the structure would be crushed and fall by its own weight. For the purpose of producing a bridge of the greatest strength with a given weight of material, the struts and suspension rods are both made less by gradations, or tapering, as they recede from the centers of resistance to tension and compression. The suspension rods are made of bars, and are solid. The struts are tubular, and made of not less than two concentric series or layers of curved plates (a) an example of which is seen in Fig. 10, which is a section of a portion of a tapering tubular strut. The plates of each series, or layer, of a tapering tube abut; and the plates of one series break joints with those of the other series. If the strut diminishes in diameter by gradations, then the plates of each layer in each gradation abut; but the plates of contiguous steps overlap. The hub, or foot (B) is of semi-cylindrical form, and may be most conveniently made of two pieces bolted together. The adjacent sides of these pieces, have recesses, to form, when the pieces are put together, a series of sockets, each of which is for the reception of the foot, or inner end of a strut, and confine it firmly in place. The shape of this foot or hub, is seen more clearly in Fig. 7, which represents it detached and on an enlarged scale.

The clamp posts are shown in detail in Figs. 5 and 6. Each post consists of two parts, one to be placed on each side of the struts, and clamped firmly together by through bolts. The recesses (c), in the adjacent sides of the two parts of the clamp posts, are to embrace the struts, so as to hold them more firmly. Or the posts may be made of flat bars, and blocks placed between the struts to fill up the spaces, the bars and blocks being firmly connected by through bolts. The suspension rods pass outside of the clamp posts, and are held in position by cleats parallel to the posts, but outside of the rods. Bolts are passed through the cleats, rods and posts, to bind the whole firmly together. In some cases, we prefer to make a single set of through bolts bind together the blocks between the struts, the clamp posts, rods, and cleats. The outer end of each section of the bridge

may be strengthened by counter braces (H) running from the outer post to the feet of the clamp posts, as represented.

The manner in which the flooring is supported on the horizontal struts, is shown in Fig. 8, which represents a transverse section of the floor of the bridge. The manner in which adjacent lengths of the suspension rods may be united is represented in detail by Fig. 9. The diagonal braces (I), under the floor of the bridge, for the purpose of giving lateral rigidity and strength to the structure, are best seen in Fig. 2.

When a section of bridge, constructed as represented and described, is mounted on a central pivot or carriage on the pier upon which it rests, so as to turn, to open a passage for vessels, or for other purposes, its connection with adjacent sections, must be such that both will be free to expand and contract, both firmly connected, and at the same time susceptible of being easily disconnected and again re-connected. These objects are accomplished by means of the device which we have constructed for uniting the terminal posts of the adjacent ends of the sections. This device is best seen in Figs. 3 and 4, the former representing the sections connected, and the latter disconnected. This device consists of two strong latch bars, (J) each pivoted to the upper end of a post, so as to be free to swing in a plane parallel to the side of the bridge, but not capable of turning in the opposite direction. The lower part of each post, at the adjacent ends of contiguous sections, is fitted with a mortise, and key, so that when the bars on the two posts are crossed, as shown in Fig. 3, and the keys placed between them, the sections will be firmly connected. The bars are detached to disconnect the two sections, as seen in Fig. 4, by the removal of the keys from the mortises.

If a bridge is only required to extend between two piers, that half of the frame which extends beyond the central post on the outer end, may be dispensed with; and the sections should in that case have no break in the middle of the span, as when the whole frame is balanced on one pier, as shown and described. A greater or less number of struts and suspension rods may be employed, according to the magnitude of the structure and the judgment of the constructor. If the bridge be built on shore, it may be transported into place, by a method recently patented by us.

The sections of the bridge may be made if deemed advisable for any reason, with the distances between the center posts and opposite ends of unequal lengths. This will in some cases be found highly advantageous in avoiding the expense and difficulty of anchoring the suspension rods at the shore end of the section.

The suspension rods may be made of either single solid bars, or of a number of flat round or other shaped bars or wires united together in any convenient way, the tapering or gradations in the size and strength of the composite rods being effected by making the parts most distant from the supports of an equal number of bars or wires with the part at the support, but of diminished thickness, or making them of fewer bars of the same thickness, as may be preferred.

Having thus described our improved bridge, what we claim therein, and desire to secure by Letters Patent, is—

1. The combination of tubular braces or struts, made smaller by gradation, or tapering as they extend from the pier or support, with suspension rods, also made smaller by gradations, or tapering as they extend from their pier or support substantially as specified.

2. We also claim the arrangement herein described of the struts, suspension rods, and clamp posts, viz;—the oblique struts between the center post, and horizontal strut, being placed in lines radiating from a common center, and the suspension rods being also placed in lines, radiating from a common center, above that from which the struts radiate, in such manner that each suspension rod shall extend from the top of the column or post (C) over the pier or support, to the foot of one of the clamp posts (F) while each oblique strut shall extend from the foot of the post (C) over the pier to the head of each clamp post, as herein described.

3. We also claim the construction of tapering tubular struts of bridges, of not less than two concentric sheets, layers, or thicknesses of metal, the sheets of each layer abutting, and those of one layer breaking joints with the next, substantially as specified.

SAMUEL CHAMPION.
THOMAS CHAMPION.
